BRIDLE BIT

Mitchel R. Braley, 504 South 74 East Ave.,
Tulsa, Okla. 74115

Filed Aug. 9, 1971, Ser. No. 170,417

Term of patent 14 years

Int. Cl. D30—04

U.S. Cl. D30—21

FIG. 1 is a side elevational view of a bridle bit, showing my new design, the opposite side being a mirror image thereof;

FIG. 2 is a front elevational view;

FIG. 3 is a top plan view; and

FIG. 4 is a bottom plan view thereof.

I claim:

The ornamental design for a bridle bit, substantially as shown and described.
